METHOD AND APPARATUS FOR INCINERATING REFUSE MATERIAL

John A. Boyd, 1310 Halloman Road, and Donald Everett Boyd, 318 University Drive, both of Fairfax, Va. 22030

Filed June 1, 1965, Ser. No. 460,389
22 Claims. (Cl. 110—8)

This application is a continuation-in-part of our pending application Serial No. 323,172, filed November 8, 1963.

This invention relates the incineration of trash, rubbish, garbage or similar combustible materials and is particularly concerned with methods and apparatus for the incineration of these combustible elements.

Various types of incinerators have previously been developed, and generally, they have proved satisfactory for use in conventional garbage collection, and in those instances where small amounts or loads of material are deposited into the incinerator for burning. However, with the general movement of family living into the suburbs, the increased use of park areas, and the recent municipal programs of trash collection, there has been a growing need for a mobile incinerator which is capable of burning large amounts of combustible material while the incinerator is moved from place to place during a day's schedule.

With mobile incineration of garbage and refuse materials, it is necessary that the incinerator completely burn the material deposited therein so that smoke and undesirable odors are not exhausted into the atmosphere. It is likewise necessary that the garbage and other materials deposited into a mobile incinerator be sufficiently burned so that the incinerator may be moved about and reloaded while it is simultaneously reducing the previous load to ash and combustion gases.

In the conventional community method of trash collection and disposal, stores, residences, and the like, dispose of their trash and garbage in barrels or garbage cans. Then, a garbage collection crew empties such barrels and cans into a truck which transports the same to dump or an incinerator. Naturally, a great amount of time, effort, manpower, and expense are involved in conducting and maintaining such services on a weekly basis and it thus would appear to be highly beneficial to provide some method and means for incinerating the garbage and trash as it is collected. The present invention accomplishes this beneficial result and thus reduces greatly, the number of collection trucks needed, the need for "dead-heading," i.e., driving empty trucks along a route, and the size requirements for community dumps and incinerators.

In addition to the community collection procedure discussed above, there is also the need for trash and garbage collection in recreation areas such as parks, beaches, zoos, golf courses, trailer camps, refreshment stands, camping areas, and the like. Many of these areas are not adequately serviced by a city garbage collection crew, and consequently, the problem of collecting trash and garbage from these areas is even more acute. Moreover, since these areas are often densely wooded, trash must be transported a considerable distance before it can be burned. The present invention not only facilitates collection of garbage and trash at such recreation areas, by virtue of its transportability, but additionally, assures that such trash can be incinerated on site, regardless of the wooded nature of such site.

Accordingly, one of the primary objects of the present invention is the provision of a mobile incinerator of the type capable of completely burning refuse material so as to eliminate undesirable odors and excessive smoke exhaust therefrom. Another primary object of the present

invention is the provision of a method of burning and filtering combustible components entrained in an exhaust gas flow from an initial combustion within a movable incinerator.

5 A further object of the present invention is to provide an improved mobile destructor incinerator for burning garbage or similar combustible material within a combustion area and providing sufficient space within the mobile incinerator for the accumulation of burnt fly-ash so that successive loading and burning operations may be carried out without necessitating excessive dumping of the ashes produced by burning.

Another object of the present invention is to provide a method of burning combustible material within a combustion area and directing the exhaust gases produced therefrom into separate gas streams flowing along prescribed paths through a plurality of chambers so as to reduce the amount of smoke and undesirable odors therein. A still further object of the present invention is to provide a method of combustion, which method includes the steps of burning, cooling exhaust gases, re-burning the gases and directing the same over a liquid so as to remove substantially all solid material therefrom before discharge into the atmosphere. In this regard, it is a further specific object hereof to provide a plurality of chambers within an inner casing so as to carry out the prescribed methods of operation referred to herein.

A still further significant specific object of the present invention is to provide a method and apparatus of burning combustible material within a primary combustion area and exhausting combustion gases therefrom into a secondary combustion area. More particularly, it is a specific object of the present invention to provide such a method and apparatus which incorporates various deflection devices for directing combustion gases in a plurality of turbulent paths and through various chambers within a mobile destructor incinerator.

Aside from the foregoing more basic general and specific objects of the invention, there are certain additional objects hereof, which are of significance. These additional objects include: (a) the provision of a method and apparatus for burning combustible material in a mobile destructor incinerator, which method and apparatus includes the induction of a continuous air flow throughout an entire combustion area of the incinerator; (b) the provision of such a method and apparatus wherein an induced draft flow developed within an incinerator casing permits the flow of exhaust gases from a first combustion area into a plurality of gas streams flowing around a second combustion area and passing therethrough to a plurality of openings in the surrounding walls thereof; (c) the provision of such a method and apparatus wherein the flow of exhaust gases into the secondary combustion area is directed along oppositely axially aligned paths and wherein the flowing gas streams meet at a point within the secondary combustion chamber so that a flame may be introduced at this point for burning the gas streams and any solidified matter thereat; (d) the provision of such a method and apparatus which directs the burnt gases into a plurality of paths throughout the secondary combustion area and directs the same over a liquid bath and into the atmosphere through an exhaust stack.

In regard to the specific apparatus for carrying out the prescribed methods of burning and exhausting combustion gases from a plurality of combustion chambers, such apparatus is characterized by: (a) the provision of a mobile destructor incinerator having primary and secondary combustion chambers for burning refuse and combustible gases therein and discharging an exhaust flow substantially free of fly-ash into the atmosphere; (b) the provision of a mobile destructor incin-

erator mounted on a wheeled frame which is provided with means for attaching the same to a powdered vehicle; (c) the provision of a mobile destructor incinerator having an outer enclosure housing and an inner cylindrical casing which houses a plurality of compartments therein and wherein the space between the outer housing and the inner casing permits a cooling flow of air therebetween so as to reduce the temperature within the inner casing; (d) the provision of a mobile destructor incinerator having an inner casing and a liquid bath chamber in the bottom portion thereof which chamber is connected by means of conduits to an ash chamber or pit so that discharge of liquid from the liquid bath chamber may be directed into the ash chamber so as to extinguish burning matter therein and to wash and clean the same; (e) the provision of a mobile destructor incinerator having a primary combustion area disposed above a plurality of reciprocally movable grates separating the primary combustion chamber from an ash chamber or pit and which grates have control means attached thereto for operation of the same.

In accordance with the present invention, refuse or other combustible material is initially deposited into a primary combustion area and burnt therein. The resultant gas streams are directed around and into a secondary combustion chamber for secondary burning therein. The gases are then directed down over a liquid bath for removing any undesirable odors and fly-ash from the gas streams before exhausting the same into the atmosphere. These are the broad and basic features of the invention, and the invention itself will be better understood by reference to the following detailed description. Such description makes reference to the accompanying drawings which present the various embodiments hereof.

In the drawings:

FIGURE 1 is a side elevational view, partially cutaway, of a mobile destructor incinerator constructed in accordance with one embodiment of the invention;

FIGURE 2 is a perspective view of an inner casing of the incinerator embodiment of FIGURE 1 with a diagrammatic showing of the air flow therein;

FIGURE 3 is a vertical sectional view through the inner casing taken along the lines 3—3 of FIGURE 2;

FIGURE 4 is a plan view of the inner casing shown in FIGURE 2;

FIGURE 5 is a plan view of the mobile incinerator shown in FIGURE 1;

FIGURE 6 is a fragmentary vertical sectional view through a portion of the outer housing of the incinerator and diagrammatically showing the cooling air flow around the inner casing;

FIGURE 7 is a perspective view of another embodiment of mobile incinerator in accordance with the present invention;

FIGURE 8 is a fragmentary side elevational view, partially broken away, showing the rear portion of the embodiment of FIGURE 6;

FIGURE 11 is a sectional view taken along the line 11—11 of FIGURE 10;

FIGURE 12 is a fragmentary perspective view of the pipe arrangement utilized in the embodiment of FIGURE 7;

FIGURE 13 is a sectional view, similar to FIGURE 3, but showing the interior of the inner casing of the embodiment of FIGURE 7, and

FIGURE 14 is a fragmentary side elevational view of the slide step unit utilized on the embodiment of FIGURE 7.

In the first embodiment of the invention shown in FIGURES 1-6, the mobile destructor incinerator is gen-

erally designated 2 and comprises an outer housing 6 within which a plurality of combustion areas are disposed and a mobile supporting frame for supporting the outer housing 6. The mobile supporting frame 4 includes a hitch 8 and a front wheel support 10. It should be understood however, that the mobile destructor incinerator 2 may also be mounted on a truck chassis and thereby do away with the necessity of a hitching device at the forward end thereof. A pair of wheels 12 are journaled on the axle 14 at the rear portion of the support frame 4. A longitudinally extending chassis 16 is supported by the wheels 10 and 12 along with co-operating springs all of which are conventional vehicle body components. A pair of wheel cowlings 18 are supported on the outer housing 6 above each wheel 12. Reflecting means 20 along with the back-up lights or stop-lights 22 are mounted on the rear end of the outer housing 6. The cut-away portion of FIGURE 1 shows a storage compartment 24 within which propane gas tanks 26, 28, 30 and 32 are supported by means of a crib 34. The gas storage tanks are connected with their conduits at 36 and 38 so that sufficient gas flow is maintained to the burners 44 and 54, the operation of which will be described below.

At the rear end of the outer housing 6 a pair of charging doors 40 are pivotally mounted on the charging extension 42 of the outer housing. An operating gas burner 44, using propane gas fuel and receiving the same from the tanks 30 and 32 is provided with a nozzle extending into the primary combustion chamber 46. By means of a circulator 48 and through the conduit 50 propane gas flows from the gas storage tanks to the burner 44 mounted on the rear of the outer housing. As more fully explained below, a pair of quick draft units 52 are mounted on the rear wall within the storage compartment 24 as is another gas burner 54 shown in FIGURE 1.

The outer housing 6 supported on the frame 4 encloses a cylindrical inner casing generally designated by the reference numeral 56. The inner casing 56 is provided with a plurality of chambers therein to be more fully described below. The primary combustion chamber 46 is disposed above a plurality of reciprocally movable grates 58 at the rearward end of the inner casing. The grates are longitudinally movable by means of the handles 60, 62, 64 and 66 protruding rearwardly from the inner casing and through the outer housing so that an operator may manipulate the grates from the rear end of the incinerator. An ash pit or chamber generally designated by the reference numeral 68 is disposed in the area below the primary combustion chamber and separated by the reciprocally movable grates 58. This ash pit or chamber 68 extends downwardly below the frame 4 and has an inclined surface 70 and access door 72 disposed below the outer housing 6 and the frame 4 as more clearly seen in FIGURE 1. In this manner, it is possible for the fly-ash accumulated within the chamber 68 to be removed therefrom at desirable intervals of time.

Extending from the upper edge of the ash pit 68 and at the forward portion of the primary combustion chamber 46 is an upstanding deflection wall 74 having its edge portions 76 and 78 abutting up against the sides of the inner casing 56 and terminating in a pair of horizontal sections 80 and 82, respectively. The deflection wall 74 then continues upwardly at the medial portion thereof designated by the reference numeral 84, to the top of the inner casing 56. By means of the cut-out sections defined by the outer walls of the inner casing, the horizontal surfaces 80 and 82, and the vertical surfaces 81 and 83, a pair of passageways are provided so that the exhaust gases produced in the primary combustion area 46 may flow therethrough.

As shown in FIGURE 2, the flow paths for the combustion gases exhausted from the primary combustion area 46 are designated by a plurality of arrows. A pair of partition walls 86 and 88 extend forwardly from the de-

fection wall 74 to the rear of the inner casing 56 and terminate at the rear wall 90 thereof. These partition walls 86 and 88 also extend vertically from the top of the inner casing to the bottom wall 92 thereof. A pair of passageways 94 and 96 are disposed at the forwardmost and bottom portions of the partition walls 88 and 86, respectively, which permits the exhaust gases from the primary combustion chamber to pass through the partition walls and into a secondary combustion chamber 98. In order to direct the exhaust gas streams through these passageways 94 and 96 in the partition walls, it is necessary to provide a deflection wall 100 in the pathway 104 and a deflection wall 102 in the pathway 106 so that the gas streams are evenly directed into the secondary combustion chamber.

As more clearly seen in FIGURE 4, the exhaust gas streams from the primary combustion chamber 46 are directed laterally of the pathways 104 and 106 along opposite axially aligned paths and into the secondary combustion area so as to turbulently mix the gas streams at the bottom central portion thereof. At this mixing point for the meeting exhaust gas streams another gas burner 54 introduces a flame designated by the arrow 110 into the secondary chamber at the bottom central portion thereof so as to further burn the mixed gas streams flowing thereto. In this manner, solid matter which was not previously reduced to fly-ash within the primary combustion chamber is here burnt so as to substantially remove all solid matter from the flowing gas streams and also to remove undesirable odors therefrom.

As best shown in FIGURES 3 and 4, the mixed exhaust gas streams from the primary combustion chamber 46 and the gases produced by the secondary burning in the secondary combustion chamber 98 will turbulently flow into the face of a first deflection baffle 112. This baffle is supported on the floor 92 within the secondary combustion chamber and extends transversely between the upstanding partition walls 86 and 88. Because of the concavity of the face of this deflection baffle 112 the mixed gas streams and exhaust gases are directed upwardly and forwardly as shown by the arrows in FIGURE 3, into the upper corner 99 of the secondary combustion chamber. As also indicated by the continuing arrows, the mixed gases will flow downwardly and rearwardly along the top portion of the secondary combustion chamber 98 toward the rear thereof. A second deflection baffle 114 depending from the top wall 116 of the inner casing 56 and extending transversely between the partition walls 88 and 86 directs the flowing gases downwardly and rearwardly through a passageway 118 at the rearward end of the bottom surface 92 within the secondary combustion chamber.

Between the bottom wall 120 of the inner casing 56 and the bottom wall 92 of the secondary combustion chamber 98 and the pathways 104 and 106, and extending transversely between the cylindrical surfaces of the inner casing is a chamber 122 in which a liquid 124 is disposed therein. As seen in FIGURE 3, this chamber 122 extends the full length of the inner casing 56 in the bottom portion thereof and between opposing side portions. The liquid 124 within this chamber 122 is maintained at a level whereby an air space 126 is created between the bottom of the floor 92 and the water level 125. This air space 126 provides a pathway for the gases entering the chamber 122 through the passage 118 in the secondary combustion chamber 86 and permits the gases to flow over the liquid and forwardly within the chamber to a pair of outlets 128 at each side of the chamber 122.

The purpose of passaging exhaust and combustion gases over the liquid bath 124 through the chamber 122 is so that all remaining fly-ash present in the gases may settle into the water 124 while the gases pass thereover. Moreover, remaining undesirable odors in the gas streams will also be removed by the passage of the same over the water bath 124. The outlets 128 disposed at the forward end

of the chamber 122 communicate with a pair of draft stacks 130 and 132 extending upwardly from the liquid bath chamber 122 and through the top wall 116 of the inner casing 56 terminating at their upper ends 134 and 136, respectively, below the top portion of the outer housing 6. As best seen in FIGURE 5, the top portion of the outer housing 6 has an expanded metal exhaust screen 138 extending from the rear end of the housing to the inner wall of the storage compartment 24. The expanded metal exhaust screen 138 permits the exhaust gases to flow into the atmosphere from the inner casing 56.

At the forward end of the liquid bath chamber 122, a conduit 140 extends rearwardly therefrom and enters a valve 142 having a control 144 for opening and closing the valve 142. Extending rearwardly from this valve is another conduit 146 entering the forward portion of the ash pit or chamber 68. In this manner, at the end of a working schedule, the fly-ash within the pit 68 may be discharged therefrom by means of the liquid flowing from the liquid bath chamber 122 through the conduits and valve disposed between the liquid bath chamber and the pit 68, while at the same time any burning matter within the pit 68 is thereby extinguished.

In order to maintain the temperature of the inner casing within an acceptable range, it is necessary to cool the outer surface of the inner casing by means of an air flow thereabout. For this purpose an air space 148 is provided between the outer surface of the inner casing 56 and the inside of the outer housing 6. This is best shown in FIGURE 6 wherein the arrows indicate the flow path of the cooling air which enters through the ports 150, 152, and 154 in the bottom portion of the outer housing 6. By means of the air vanes 156, 158, 160 and 162, air is forced into the cooling area 148 while the incinerator is being transported from place to place. This cooling air flows around the inner casing within the area 148 and is exhausted through the expanded metal screen 138 at the top of the housing 6. In order to more efficiently cool the incinerator and the inner casing, the pair of quick draft fans 52 are provided and mounted on the forward end wall 170 separating the air space 148 and the storage area 24. These quick draft fans 52, as seen in FIGURE 6, circulate an air flow through the air space 148 as well as serving another purpose to be described below. Accordingly, the forced air draft through the ports at the bottom of the outer housing combined with the circulating air caused by the draft fans 52 sufficiently cools the inner casing so as to maintain the desired temperature range therein.

The quick draft fans 52 previously mentioned induce a forced air throughout the inner casing so that the aforementioned gas streams are pulled from the primary combustion area 46 through the passageways 104 and 106 and into the secondary combustion area 98. The gas streams are directed in a plurality of turbulent paths through the secondary combustion area and then directed into and over the liquid within the liquid bath chamber 122 and then exhausted through the stacks 130 and 132. In other words, the quick draft fans 52 serve a dual purpose of exhausting the combustion gases from the inner casing while simultaneously creating a cooling air flow within the air space 148 about the inner casing for cooling the same. These quick draft fans 52 are of the conventional venturi tube type and do not constitute a part of the present invention.

By means of the movement of the entire mobile destructor incinerator during its transportation from place to place, the fly-ash in the liquid within the chamber 122 is thereby caused to sink to the bottom thereof to be later transferred at the end of the working schedule to the ash pit where the flowing liquid extinguishes any burning in the ashes and further cleans and discharges the ash therefrom as previously described.

With the provision of a mobile destructor incinerator utilizing propane gas storage tanks and gas burners

within primary and secondary combustion areas, and with the forced air draft induced by the quick draft fans throughout the inner casing, it is therefore possible to burn garbage and other material at a sufficiently high rate of speed which enables the operator to move about through his garbage pick-up schedule without returning to the plant for discharge of the burnt ash. Since the burning takes place while the mobile destructor incinerator is being transported from place to place, it is not necessary to remain at one location in order to first load and then burn the material within the incinerator. Furthermore, through the use of a secondary burning and through the use of a liquid bath it is further possible to remove substantially all solid materials and undesirable odors from the flowing exhaust gas streams so that the exhaust from the incinerator does not become a nuisance to home owners, park users and other people who may be within the vicinity of the moving incinerator.

Referring now to the second embodiment of the present invention, there is shown in FIGURE 7 a larger and somewhat modified form of mobile incinerator generally designated 200. The incinerator 200 includes an outer casing 202 mounted upon a suitable vehicular frame carrying four wheels 204. The casing may be provided with a pair of fenders 206 extending across the wheels. The forward portion of the incinerator forms an equipment room to which access may be gained by a door 208. On the sides at the rear of the vehicle, riding steps are provided to permit personnel to be carried by the vehicle while the same is being pulled. A fixed riding step 210 may be provided at one side of the vehicle, and a slideable step 212 may be provided at the opposite side thereof. As shown in FIGURE 14, the slide step 212 may be moved between an extended position, shown in dashed lines, which permits someone to stand thereon, and a recessed position whereat the step is slid under the housing 202. A handle 214 can be provided on the rear of the housing so that an operator may hold the same while he rides on the slide step 212. Also, a signal button 216 may be provided on the casing, such button being useful to permit an electrical signal to be sent from the rear of the incinerator to the cab of the vehicle towing the incinerator, thereby indicating to the driver that he should either commence or terminate towing.

Just as in the initially described embodiment, there is provided within the outer casing 202, an inner casing 218 which is spaced inwardly sufficiently from the walls of the outer casing 202 to establish an air space therebetween. At the rear end of the housing, a pair of hinged charging doors 220 are provided, with a hinged baffle 222 hanging downwardly inside such doors. Inside the housing adjacent the doors 220, there is provided a primary combustion chamber generally designated 224 and having grate members 226, slidably mounted therein in the same manner as previously described in connection with FIGURE 2. An ash pit 228 is provided beneath the grates 226, to accomplish the purposes previously set forth in connection with the initial embodiment hereof. Somewhat centrally of the incinerator 200, in upstanding relationship interiorly of the inner casing 218, there is provided a divider or deflection wall 230 which serves to set off the primary combustion chamber 224 from a secondary combustion chamber generally designated 232 which is disposed between the deflection wall and the equipment room.

To more fully appreciate the construction and significance of the primary combustion chamber 224, reference is made to FIGURES 8 and 9 wherein it can be seen that the grates 226 are provided with handles 234 which may be manipulated by the incinerator operator. The side walls of the primary combustion chamber 224 are formed as corrugated baffles 226, fabricated of stainless steel or other similar material which will withstand the heat of combustion within the chamber. These combustion walls 236 are spaced somewhat inwardly from

the walls of the inner casing 218 to thus provide a narrow passageway 238 therebetween. Beneath the inner casing 218, a depending insulation wall 240 extends downwardly to the frame of the vehicle, thus continuing 5 the passageway 238 to a position spaced just above the ground. Ambient air for combustion is drawn inwardly from the bottom of the incinerator, and such air passes upwardly through the passageways 238 on opposite sides of the primary combustion chamber 224. As such air passes the walls 236, it is pre-heated by radiation from such walls, and such pre-heating thereby assures improved combustion within the primary chamber 224. Additionally, a pair of blower fans may be provided in spaced 10 housings 242 on opposite sides of the doors 220, and an interconnecting conduit 244 may extend between such 15 housings. The blower fans can aid in inducing a flow of ambient air into the primary combustion chamber. An operating gas burner may be provided in one or both 20 of the housings 242, with such burner means having a nozzle 246 extending into the primary combustion chamber, as shown in FIGURE 8. Liquid propane gas is supplied from a source thereof, to be presently described, 25 and passes through lines 250 shown in FIGURE 7, to be supplied to the burners and to pass through the nozzle 246 into the primary combustion chamber. The admixture of such liquid propane gas and pre-heated air in the primary combustion chamber 224 creates a combustion supporting atmosphere therewithin which enables the garbage and trash introduced through the charging 30 doors 220 to be burned. Such burning takes place upon the grates 226 and the ashes and residue then drop through such grates into the ash pit 228. The ash pit is provided with a slidably removable bottom 252 which 35 can be manually extended at periodic intervals to allow the ash residue to drop into the street or onto a dumping area. If such ash residue drops into the street, it can be manually picked up and placed within the truck or towing vehicle which pulls the incinerator 200.

The deflection wall 230 in the embodiment of FIGURES 7-14 is essentially the same as the deflection wall 74 previously described in that it has an upstanding central section 254 which extends to the top of the inner casing 218, and a pair of laterally extending shoulders 256, 256 extending sidewardly from the central section 254 to merge into the side walls of the inner casing 218. The space between the shoulders 256 and the interior of the casing 218 thus sets off a pair of spaced passageways 258, 258 extending longitudinally of the incinerator on opposite sides of the central wall section 254. The exhaust gases from the primary combustion chamber 224 40 pass into these passageways 258 and additionally, a certain amount of the preheated air from the passageway 238 passes therewith. To aid in the mixing of these primary combustion gases, with the preheated air, a pair 45 of baffle members are provided, each baffle member being a plate 260 extending angularly forward from the shoulder 256 and having a plurality of apertures 262 therein. Side or partition walls 264, 264 extend forwardly from the edges of the central portion 254 on the deflection wall, 50 to thereby establish therebetween, the secondary combustion chamber 232.

The interior of the secondary combustion chamber 232, as can best be seen from FIGURE 13, corresponds substantially to the configuration previously described in connection with FIGURE 3 relating to the initial embodiment of invention. That is, the top of the secondary combustion chamber is formed by the top wall of the inner casing 218, the rear wall of the secondary combustion chamber is formed by the deflection wall 230, and the 55 forward wall of the secondary combustion chamber is formed by a wall 266. Openings 270 are provided in each of the side walls 264 whereby the divided exhaust gas streams flowing through the passageways 258 may be directed into the secondary combustion chamber 232 60 by means of upstanding deflection walls 272, as shown in

FIGURE 7, and being similar to the walls 100, 102 previously described. Within the secondary combustion chamber, a bottom or base wall 276 is provided with a first arcuately formed deflection baffle 278, similar to the baffle 112 of the previously described embodiment. A second arcuately formed deflection baffle 280, similar to the previously described baffle 114, depends from the upper wall of the inner casing 218. The gas streams in the secondary combustion chamber 232 are turbulently directed, as shown by the arrows, and as previously described in the initial embodiment, and are directed downwardly to the passageway 282 between the base wall 276 and the deflection wall 230.

The passageway 282 leads to a main liquid bath or reservoir generally designated 284 which exists beneath the secondary combustion chamber and which carries therewithin a supply of water or other suitable liquid 15 286. The purpose for passing the gases from the secondary combustion chamber over and across the liquid bath 284, is to assure that all remaining fly-ash present in the gases will settle into the water 286 within the bath. Baffle means 288 can depend from the underside of the base wall 276 and into the bath 284 to be assured that the gases follow a somewhat tortuous path while passing through the bath, thereby assuring that undesirable odors will likewise be removed from the exhaust gases. One or more upstanding draft stacks 290 are provided at the forward end of the bath 284, whereby the gases which have passed across the bath can exit upwardly through such stacks.

As shown in FIGURE 7, the top of the outer housing 202 is open, and is provided with a plurality of sidewardly or laterally extending louvers or baffles. The louvers 292 at the forward portion of the incinerator are directed angularly rearwardly while the baffles 294 at the rearward portion of the incinerator are directed angularly forwardly. As will be seen, the draft stack or stacks 290 terminate beneath the baffles 292, and thus the gases exhausting from such stacks pass through the louvers 292 and are directed rearwardly, particularly when the incinerator is moving in a forward direction, as is usual when the incinerator is being pulled by a towing vehicle. Similarly, because of the forwardly disposed relation of the louvers 294, towing of the incinerator causes cooling air to enter inwardly through such louvers and to pass around the sides of the inner casing 218, thereby serving to cool the same. At the very forward portion of the incinerator, above the equipment room, no louvers are provided, and instead, a sloped solid wall portion 296 is provided. This wall portion, as can be seen from FIGURES 7 and 10, slopes upwardly and terminates in an upstanding lip 298. Thus, as the incinerator 200 is towed in a forward direction, the coaction of the sloped wall 296 and the lip 298 serve to assure that the ambient air will not pass directly across the louvers 292 and 294, but instead, will be directed somewhat upwardly to pass over the incinerator. In this manner, it is virtually assured that the exhaust gases exiting through the louvers 292 will not be re-directed back through the louvers 294.

In the forward portion of the incinerator, i.e., the equipment room, the supply of liquid propane gas is maintained in a large tank 300 located within a chamber 302. A generator 304 is located above this room 302 and louvers 306 in the forward wall of the incinerator permit cooling air to pass across the generator. An opening 308 is formed beneath the generator 304 to communicate with the chamber 302, to thereby heat the atmosphere therebetween, thus assuring better vaporization of the gas in the tank 300. Additionally, if desired, a separate coil heater may be utilized in conjunction with the tank 300. Another chamber 310 is provided at one side of the equipment room, such chamber having the incinerator radiator 312 therein, which radiator communicates with the atmosphere via louvers 314 in the outer

casing 202. A fan 316 is provided behind the radiator 312 to draw the air inwardly through the louvers 314 for cooling purposes. An additional draft fan 318 may be provided in the equipment room to ventilate the same 5 through louvers in the door 208.

In contrast to the initial embodiment of invention wherein all of the liquid or water for the bath was carried directly therewithin, and wherein such water had to be periodically refurbished from a fire hydrant or the like, this embodiment of invention carries a pair of auxiliary water tanks 320, 320, disposed along the sides of the inner casing 218 as shown in FIGURE 9. These water tanks 320 are also disposed along the sides of the main bath 284, as can best be seen in FIGURE 12. The piping system keeps the water from the tanks 320 in constant circulation with the water in the tank 284, thereby permitting the water tanks 320 to actually act as water jackets which provide a cooling effect along the sides of the combustion chamber. To this end, a line or conduit 322 extends between the side tanks 320 and connects to a central pipe 324 which in turn connects to a line 326 having a portion 328 which takes water inwardly from the main bath 284. A branch line 330 leads from the line 326 to a water pump and motor 332 which operates to keep the water in constant circulation. Another branch line 334 connects the pump 332 back to the line 326, thereby permitting the desired circulatory effect. An additional branch line 336 extends into the tank 284 and to a spray head 338, shown in FIGURES 10, 12 and 13. 15 30 This spray head 338 provides a spray of water in the space in the main bath above the liquid level 286, and the exhaust gases exiting from the bath 284 must pass through this spray thereby giving such gases even an additional wetting treatment. A flow switch 340 may be 35 provided in the line 334 to act as a sensor for determining whether there is continuous water flow through the piping system. If, due to failure of the pump 332, clogging of the pipes, or some other similar defect, the water should fail to properly circulate, this flow switch 340 activates an alarm system to indicate to the operator that the unit is not functioning properly. Overflow pipes 342, 342 extend from the side tanks 320 to the main bath 284. Thus, as the pump 332 operates, it draws water 286 inwardly from the main bath via the intake 328. Most of such water is transferred through the lines 334, 322 and into the side water tanks 320, from which such water can exit through the overflow pipes 342 to be returned to the main bath 284. In this manner, the water is constantly kept in circulation and thereby serves to provide 40 a cooling effect for the combustion chambers. A certain amount of the water being circulated is passed through the line 336 to the spray head 338, for the purpose previously described. 45 50 55

As an additional feature, a thermocouple 344 is provided in the forward wall 266 of the secondary combustion chamber. This thermocouple is electrically connected to sense the heat in the secondary combustion chamber 232, and when such heat reaches approximately 1400° F. the burners in the primary combustion chamber are automatically cut off, since the heat therein will be high enough to assure spontaneous combustion therewithin.

As shown in FIGURE 13, the bath 284 may be connected to the ash pit 228 by means of a conduit 346 having a valve 348 therein. This is similar to the arrangement described in connection with FIGURE 3, and accomplishes the same purpose, namely, to permit selective transfer of water 286 from the main bath to the ash pit for washing the same.

Before discussing the operation of the second embodiment hereof, it will be apparent that in this embodiment, as well as the embodiment initially described, mobility of the incinerator is one of the features which enables accomplishment of the objects of the present in-

vention. Accordingly, to this end, it is customary to form the incinerator 200 as a separate trailer unit which can be attached to any suitable towing vehicle by means of a hitch, such as the hitch 350 shown in FIGURE 10. Preferably, the towing vehicle will be in the form of a truck which can itself collect and carry the burnt refuse from the ash pit 228.

Although the operation of this second embodiment of invention is substantially the same as that of the initial embodiment, and although such operation should be somewhat apparent from the detailed description set forth hereinbefore, such operation will again be herein described in a brief manner, to assure an understanding of the novel and important aspects of the present invention. Let it be assumed that the incinerator 200 is operating and that the same is being towed by an automotive vehicle from one location to another. When the vehicle reaches the second location, whereat the garbage and refuse to be burnt are located, the towing vehicle stops and the operator opens the charging doors 220 at the rear of the incinerator. A conventional switch means is provided on the doors, whereby when such doors are opened, the flow of gas through the lines 250 is terminated, for safety purposes. The refuse or garbage is then introduced through the doors into the primary combustion chamber 224 to rest upon the grates 226 therewithin. The hanging baffle 222 serves to assure that bottles, aerosol cans, or other explodable items previously introduced into the combustion chamber, cannot explode and cause any harm to the operator. When the trash has been successfully loaded into the primary combustion chamber, the operator closes the doors, climbs upon the slide step 212, and pushes the button 216, thereby signaling the operator of the towing vehicle that the loading operation has been completed and that the incinerator can again be moved to the next location. Ambient air is drawn inwardly through the passageways 238, wherein it is pre-heated by radiation from the primary combustion chamber. A portion of this pre-heated air passes into the primary combustion chamber, along with liquid propane gas supplied from the tank 300. A gas burner 246 ignites the combustible mixture within the primary combustion chamber, thereby causing refuse to be burnt therewithin. The ashes and solid residue from such combustion drop through the grates 226 and into the ash pit 228. Meanwhile the exhaust gases from the primary combustion chamber, which carry a certain amount of fly-ash entrained therein, are divided by the deflection wall 230 into a pair of separated streams flowing through the passageway 258. The baffles 260 within these passageways mix the remainder of the pre-heated air with these exhaust streams, and the mixed stream then flows forwardly to the deflection walls 272 which direct the mixed gas stream inwardly through the openings 270 and into the secondary combustion chamber 232. A secondary gas burner 352 is provided at the forward end of the secondary combustion chamber, and is connected by a line 354 to the gas tank 300. This burner 352 creates a secondary burning action within the chamber 232 to thus burn the solid fly-ash and other matter entrained within the mixed gas stream. The baffles 278 and 280 cause the mixed gas stream to flow turbulently about within the secondary combustion chamber, thereby assuring a complete secondary burning operation.

Once the gases have been burned within the secondary combustion chamber, they pass through the passageway 282 to the main bath 284 having a liquid such as water 286 disposed therewithin. As the gases pass across the surface of this water 286 any remaining fly-ash present therein will settle into the water, and additionally, the water will serve to remove any objectionable odors present in the gas stream. The gases pass forwardly through the bath 284 toward draft stack means 290, with the baffle 282 assuring that such flow will be tortuous rather

than direct. As the gases flow to the draft stack means 290, they pass through a spray from the spray head 338, which provides a further wetting action to assure that no fly-ash or solid matter remains within the gases. The 5 then purified gases exit upwardly through the draft stack 290 and discharge through the louvers 292 at the top of the unit.

Among the features which enable the instant invention to operate in its highly efficient manner, is the 10 provision of the incoming ambient air passing through the passageways 238, and thereby being pre-heated to assure better initial combustion in the primary combustion chamber. Also, the reverse angular disposition of the louvers 294 at the top of the unit assures that cooling air will 15 be drawn inwardly to pass between the inner and outer casings. Moreover, the provision of the side water tanks 320 serves to provide cooling water jackets which absorb the heat of the combustion, and the piping system and 20 circulating means assure that the water, both within the side tanks and main tank, are in constant circulation. An audible or visible alarm system is linked with this water circulating system to thus provide an indication to the operator in the event that the water circulating system should fail for some reason. To assure better vaporization of the liquid propane gas, a coil heater can be provided for the tank 300, and auxiliary heating can be accomplished by means of indrawn air passing over the generator 304. The generator itself exhausts through a 25 pipe 356 in the rear of the lip 298, so that such exhaust is not directed into the equipment room of the unit. An even further additional heating effect for the tank 300 may be provided by the radiator 312 which heats the air 30 passing thereacross from the adjustable louvers 314. Also, the thermocouple means 344 serves to coil and 35 control combustion in the primary combustion chamber responsively to the temperature in the secondary combustion chamber.

After reading the foregoing detailed description it will 40 be apparent that the objects set forth at the outset of the specification have been successfully achieved by the present invention. Accordingly,

What is claimed is:

1. A method of burning combustible components entrained in an exhaust gas flow from a combustion chamber, said method comprising the steps of:
  - (a) directing said exhaust gas flow into separate gas streams flowing along opposite sides of a given area;
  - (b) directing said gas streams into said area along opposite axially aligned paths such that said gas streams turbulently mix at a given location in the lower portion of said area;
  - (c) subjecting said mixed gas streams to flame at said given location;
  - (d) directing the mixed gas stream rearwardly in said area and then forwardly into an upper portion of said area;
  - (e) re-directing the mixed gas streams rearwardly in the upper portion of said area, and then,
  - (f) directing the mixed gas streams downwardly below said area and over a body of liquid.
2. A method of burning refuse in a first combustion area and exhausting combustion gases produced by said burning, said method comprising the steps of:
  - (a) directing the combustion gases upwardly and forwardly of said first combustion area and into a plurality of gas streams flowing on opposite sides of a second combustion area;
  - (b) directing said gas streams on each side of said second combustion area downwardly and inwardly into said second combustion area so that said gas streams are flowing in opposite axially aligned paths;
  - (c) mixing said gas streams at a given location within said second combustion area;
  - (d) burning the mixed gas streams at said given location.

13

- tion within said second combustion chamber so as to remove substantially all of the smoke and combustible particles therein;
- (e) directing the mixed gas streams and combustion gases produced by said burning rearwardly, upwardly and forwardly in said second combustion area; 5
- (f) re-directing said mixed gas streams and the combustion gases from said burning rearwardly in said second combustion area;
- (g) directing said mixed gas streams and said combustion gases downwardly and below said second combustion area into a washer area; 10
- (h) passing said mixed gas streams and said combustion gases forwardly over a liquid so as to substantially remove all remaining ash in said gas streams, and 15
- (i) directing said ash-free gas streams into the atmosphere.
3. A mobile destructor incinerator for burning refuse therein and discharging combustible gases therefrom comprising: 20
- (a) a wheeled supporting frame;
  - (b) an outer housing;
  - (c) an inner casing spaced from said outer housing so as to permit a cooling air flow between the inner side of said outer housing and the outer side of said inner casing; 25
  - (d) first gas burner means mounted on said outer housing having a nozzle disposed within said inner casing;
  - (e) a first combustion area within said inner casing for burning refuse therein by means of said first gas burner means; 30
  - (f) a refuse charging passageway in said outer housing communicating with said first combustion chamber and having door means thereon for opening and closing said passageway; 35
  - (g) a first upstanding deflection wall disposed forwardly of said first combustion chamber and opposite said refuse charging passageway,
    - (1) outlets in said first deflection wall for permitting the combustion gases produced in said first combustion chamber by said first gas burner means to flow therefrom;
    - (h) a second combustion chamber having a second gas burner associated therewith for removing smoke and odors from said combustion gases produced in said first combustion chamber; 45
    - (i) means for directing the flow of combustion gases between said first and said second combustion chamber; 50
    - (j) first baffle means in said second combustion chamber for directing the combustion gases upwardly and forwardly therefrom;
    - (k) second baffle means for directing said combustion gases downwardly and rearwardly therefrom; 55
    - (l) washer means underlying said second combustion chamber,
      - (1) inlet means communicating with said second combustion chamber for permitting said combustion gases to flow from said second combustion chamber and over said washer means, 60
      - (2) outlet means in said washer means disposed forwardly of said inlet means;
      - (m) means associated with said first and second combustion chambers and said washer means to induce a draft throughout said inner casing so as to create said flow of combustion gases.

4. A mobile destructor incinerator comprising:

    - (a) a longitudinally extending support frame having wheel means thereon; 70
    - (b) an outer housing mounted on said frame;
    - (c) an inner casing supported within said outer housing and having the walls thereof spaced inwardly from the inner surface of said outer housing so as to provide a cooling chamber therebetween;

14

- (d) charging doors pivotally supported on the rear of said outer housing;
- (e) a primary combustion chamber disposed at the rearward end of said inner casing,
- (1) said primary combustion chamber including a plurality of grates removably disposed at the bottom thereof;
  - (2) an ash pit disposed below said grates for collecting the ash produced during combustion;
- (f) an upstanding deflection wall at the forwardmost portion of said primary combustion chamber;
- (1) said deflection wall comprising a pair of cut-out sections;
  - (g) a pair of longitudinally extending upstanding partitions disposed between said upstanding deflection wall and the forward end of said inner casing, said partitions being spaced inwardly of said cut-out sections in said upstanding deflection wall;
  - (1) said partitions defining a first and second flow path between each partition and the inner surface of said inner casing, and a secondary combustion chamber between said partitions;
  - (2) each of said partitions having a cut-out portion providing a passageway between said secondary combustion chamber and said first and second flow paths;
  - (h) a water chamber disposed below said first and second flow paths and said secondary combustion chamber;
    - (1) said water chamber having an inlet communicating with said secondary combustion chamber and a plurality of outlets communicating with the atmosphere, and
    - (i) means supported on said frame for creating a draft throughout said inner casing so as to induce said gas flows.

5. The mobile destructor incinerator defined in claim 4 further including;

    - (a) conduit means connecting said water chamber and said ash chamber;
    - (b) valve means in said conduit between said water chamber and said ash chamber for alternatively directing a water flow into said ash chamber for cleaning the same or out of said water chamber and through said outer housing so as to empty said water chamber.

6. A mobile incinerator unit comprising:

    - (a) first enclosure means defining therewithin a primary combustion chamber;
    - (b) means communicating with said primary combustion chamber and being movable between an open position which permits said primary combustion chamber to be charged with contents to be incinerated and a closed position which prevents such charging;
    - (c) second enclosure means juxtaposed to said first enclosure means and defining therewithin a secondary combustion chamber;
    - (d) means for directing the exhaust gas stream from said primary combustion chamber into said secondary combustion chamber for effecting a secondary burning of said exhaust gas stream;
    - (e) liquid reservoir means communicating with said secondary combustion chamber for receiving the exhaust gas stream therefrom and for permitting such exhaust gas stream to pass therethrough;
    - (f) exhaust means coupled to said liquid reservoir means whereby exhaust gases exiting from said reservoir means can discharge from the unit;
    - (g) a pair of side liquid tanks disposed on opposite sides of said second enclosure means; and
    - (h) hydraulic circuit means interconnecting said side liquid tanks to said liquid reservoir means.

7. A mobile incinerator unit as defined in claim 6,

wherein said first enclosure means has grate means in the base thereof.

8. A mobile incinerator unit as defined in claim 7, wherein said first enclosure means further includes an ash receiving housing disposed beneath said grate means for receiving ashes from the incinerated contents of said primary combustion chamber.

9. A mobile incinerator unit as defined in claim 8, wherein said ash receiving housing includes a removable bottom wall for emptying the ashes therefrom.

10. A mobile incinerator unit as defined in claim 6 wherein said liquid reservoir means includes baffle means which prevent the gas stream therewithin from passing directly to said exhaust means.

11. A mobile incinerator unit as defined in claim 6 wherein said hydraulic circuit means includes pump means for keeping said liquid in circulation between said side tanks and said reservoir means, thereby permitting said liquid to provide a cooling effect for said second enclosure means.

12. A mobile incinerator unit as defined in claim 11 wherein said hydraulic circuit means further includes a flow sensing means and an alarm means coupled thereto whereby said flow sensing means will operate said alarm means if liquid circulation terminates.

13. A mobile incinerator unit comprising:

- (a) first enclosure means defining therewithin a primary combustion chamber;
- (b) means communicating with said primary combustion chamber and being movable between an open position which permits said primary combustion chamber to be charged with contents to be incinerated and a closed position which prevents such charging;
- (c) second enclosure means juxtaposed to said first enclosure means and defining therewithin a secondary combustion chamber;
- (d) means for directing the exhaust gas stream from said primary combustion chamber into said secondary combustion chamber for effecting a secondary burning of said exhaust gas stream;
- (e) liquid reservoir means communicating with said secondary combustion chamber for receiving the exhaust gas stream therefrom and for permitting such exhaust gas stream to pass therethrough;
- (f) exhaust means coupled to said liquid reservoir means whereby exhaust gases exiting from said reservoir means can discharge from the unit;
- (g) said first enclosure means including passageway means at least partially surrounding said primary combustion chamber and communicating with the atmosphere to admit ambient air to said primary combustion chamber;
- (h) said means for directing said exhaust gas stream including wall means juxtaposed to said second enclosure means and having interrupted portions therein to cause said primary combustion chamber exhaust gases to divide into a pair of streams which flow along opposite sides of said second enclosure means;
- (i) said wall means including baffle means at said interrupted portions for admixing at least a portion of said ambient air with said primary combustion chamber exhaust gases.

14. A mobile incinerator unit as defined in claim 13 wherein said second enclosure means has at least one opening in each side thereof communicating with said secondary combustion chamber and has a deflection wall juxtaposed to each such opening to direct the gas streams flowing along the sides of said second enclosure means through said openings and into said secondary combustion chamber.

15. A mobile incinerator as defined in claim 13 wherein said exhaust means includes at least one upstanding draft stack communicating with the atmosphere.

16. A mobile incinerator unit as defined in claim 15

wherein said exhaust means further includes angularly directed louvers disposed adjacent the outlet of said draft stack for directing the exhausting gases in a given direction opposite to the direction of normal forward movement of said unit.

5 17. A mobile incinerator unit as defined in claim 16 further including additional louvers juxtaposed to said louvers and angularly directed oppositely to said given direction, said additional louvers serving to draw atmospheric air into said unit during forward movement thereof, for cooling of said unit.

10 18. A mobile incinerator unit comprising: housing means; ground engaging wheel means coupled with said housing means to enable the same to be readily transported;

15 first enclosure means within said housing means defining a primary combustion chamber; second enclosure means within said housing means juxtaposed to said first enclosure means and defining a secondary combustion chamber;

20 means for charging said primary combustion chamber with contents to be incinerated, such incineration producing an exhaust gas stream; said second enclosure means including a top wall means, a bottom wall means and side walls which serve

25 to define said secondary combustion chamber; said side walls being spaced from said housing means to define passageway means;

said side walls having inlet opening means therein communicating the interior of said secondary combustion chamber with said passageway means; said exhaust gas stream flowing from said primary combustion chamber, through said passageway means and into said secondary combustion chamber; liquid bath means disposed beneath said second enclosure means whereby said second enclosure means bottom wall means forms the top boundary of said liquid bath means;

said liquid in said liquid bath means being at a level which is spaced slightly beneath said bottom wall means to thereby provide a flow space between the surface of said liquid and said bottom wall means; ignition means communicating with the interior of said secondary combustion chamber for burning the exhaust gas stream introduced thereinto;

45 said bottom wall means including an outlet opening means communicating with said liquid bath means whereby the burnt exhaust gas stream from said secondary combustion chamber can pass through said outlet opening means and along said flow space, thereby at least partially contacting the liquid in said bath means to wash said burnt exhaust gas stream; and,

50 exhaust means communicating between the atmosphere and said flow space to exhaust said washed gas stream to the atmosphere.

19. A mobile incinerator unit as defined in claim 18, wherein said bottom wall means includes depending baffle means extending at least partially into said flow space to cause the gas stream flowing therethrough to follow a tortuous path.

20. A mobile incinerator unit as defined in claim 18, wherein said bottom wall means includes an upwardly extending baffle to cause said introduced exhaust gas stream to flow upwardly toward said top wall means, and wherein said top wall means includes a downwardly extending baffle to cause said burnt exhaust gas stream to exit through said outlet opening means.

21. A mobile incinerator unit as defined in claim 18 further including burner means in said primary and secondary combustion chambers and a supply of combustible material connected with said burner means.

22. A mobile incinerator unit as defined in claim 21 including thermocouple means in said secondary com-

bustion chamber, coupled to said burner means in said primary combustion chamber to interrupt operation thereof when said secondary combustion chamber reaches a predetermined temperature.
